MULTICOLOR SOAP

Filed Sept. 11, 1928

INVENTOR.
ARTHUR HENRIKSEN
BY *Arthur Henrichsen*
ATTORNEY

UNITED STATES PATENT OFFICE

ARTHUR HENRIKSEN, OF NEW YORK, N. Y.

MULTICOLOR SOAP

Application filed September 11, 1928. Serial No. 305,233.

This invention relates generally to soaps and has more particular reference to a novel cake of soap arranged for presenting a distinctive appearance.

5 The invention has for an object the provision of an article of the class mentioned which is of simple durable construction, desirable in use and efficient in action, and which can be manufactured and sold at a reasonable cost.

The invention proposes to design a cake of soap of white color for example and insert a block of soap of any color therein to make a soap showing a center of any shape 15 that could be easily recognized. Cakes of soap generally, today, are of a solid color or molded appearance. As it is now the name of the soap is stamped on and as the soap washes away the name is lost. With the instant arrangement, however, it could be a white soap with a round centerpiece of green soap. The manufacturer could say, "You will know our soap by the green center." Very obviously, the cake of soap may be entirely used up and the distinction mark remains until the end.

It is proposed that after the soap comes out of the plodder and is cut to the right size for stamping, it should go to a machine 30 that would punch a hole of round or square shape in it. Another piece of soap of white color or any other color may be punched out, of such size and shape so as to fit within this hole. In the cake of soap this can be done 35 by having a plodder plate or die with an opening similar to the hole, the dimension naturally slightly less so that it can be inserted easily or can be punched out of other flat pieces by a punch. It might also be advisable to fill up the hole within the cake of soap by pouring melted soap into it, such as transparent soap.

When one piece of one color, or white 45 or black soap has been placed in the opening of a differently colored, or white cake of soap, it is readily seen that this organization provides a soap with a characteristic center bearing the manufacturer's trademark.

50 For further comprehension of the inven-

tion, and of the object and advantages thereof, reference will be had to the following description and accompanying drawings, and to the appended claims in which the various novel features of the invention are more particularly set forth.

55 In the accompanying drawing forming a material part of this disclosure:

Fig. 1 is a perspective view of a cake of soap constructed according to this invention.

60 Fig. 2 is a transverse vertical sectional view, taken on the line 2—2 of Fig. 1.

Fig. 3 is a perspective view of the block 65 of soap inserted in the opening in the cake of soap.

Fig. 4 is a plan view of a modified form of the article.

70 Fig. 5 is a perspective view of the center soap piece thereof.

Fig. 6 is a fragmentary sectional view similar to Fig. 2, but showing a modification thereof.

75 Fig. 7 is a fragmentary plan view of a cake of soap constructed according to modified form.

Fig. 8 is a fragmentary vertical sectional view, taken on the line 8—8 of Fig. 7.

80 The reference numeral 10 indicates generally a cake of soap of any shape, design or construction, formed with a central opening 11, and a block of soap 13 of a shape corresponding with this opening is shown engaged in the opening. The cake of soap 10 may be of any color, as indicated on the drawing it 85 is of a pink shade. Similarly, the block of soap 13 may be of any color different than the cake for forming a distinction, as indicated on the drawing which is shown black. The opening 11 and the block of soap 13 is 90 shown of elliptical shape in horizontal cross section and having lateral straight sides 14.

95 It is readily seen that as this cake of soap is used and becomes smaller in size, the distinctive block 13 will always remain within the cake and be correspondingly used, until the cake is entirely used up. Thus users of the soap, at all times, having a reminding feature that the particular soap being used is the product of a certain manufacturer.

In Figs. 4 and 5, a modified form of the article has been shown. The block of soap 13' is shown within a cake 10'. This cake of soap has a square central opening 11' and the block 13' is of a shape for engaging within this opening. As shown on the drawing, the color of the soap 10' is white and the block 13' is black. The horizontal cross section of the block 13' is of rectangular shape and the vertical sides are straight as indicated by the numeral 14'.

In Fig. 6, a cake of soap 10^a has been illustrated with a block 13^a engaged therein. The soap 10^a has an irregular opening 11^a for receiving the block 13^a. It is pointed out that the lateral sides of the block of soap 13^a are inclined downwardly from the top down to the center indicated by the numeral 15, and inclined inwardly from the center down to the bottom as indicated by numeral 16. This construction prevents accidental knocking out of the center block of soap 13^a. The soap may be used and obviously during use becomes thinner but since the angle occurring in the lateral sides of the block 13^a is at the center it will always serve to hold the block against displacement.

In Figs. 7 and 8, another modified form of the article has been shown in which a cake 10^b of soap is formed with a central opening 11^b of cylindrical form. A block of soap 13^b is shown engaged within this opening. The block of soap is formed with side extensions 17 extending its entire height and shaped 35 serrated on its outer sides as indicated at 18. The cake of soap 10^b is formed with recesses 18^a for receiving the extensions and the serrated faces of the block of soap. This construction is such that the soap may be irregularly used and still the block 13^b would 40 be held against being forced out accidentally. If for instance, the top of the soap was continually used, it is readily seen that the soap may be used nearly all the way to the bottom 45 without any danger of the central block being knocked therefrom.

While one opening and one block of soap has been shown within the cakes of soap, it is not intended as a limitation. The cake of soap may be provided with several openings and several blocks engaged within these openings.

While I have shown and described the preferred embodiment of my invention, it is 55 to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. As an article of manufacture, a cake of soap with a circular aperture extending completely through from one side to the other

and two opposite niches on the rim of the circular aperture which are formed with a plurality of pyramidal serrations at right angles to the said cake's vertical height, and a block of soap snugly engaged in the aperture and having lateral pyramidal serrations at right angles to the longitudinal length of the aperture and interengaging the said serrations for preventing accidental knocking out or rotating of the block of soap.

2. As an article of manufacture, a cake of soap with an aperture extending completely through from one side to the other and formed with serrations at right angles to its vertical height, and a block of soap snugly engaged in the aperture and having side extensions, said side extensions having lateral serrations at right angles to the longitudinal length of the aperture and interengaging the said serrations for preventing accidental displacement or rotation of said block.

In testimony whereof I have affixed my signature.

ARTHUR HENRIKSEN.
